UNITED STATES PATENT OFFICE.

SAMUEL GRIFFIN, OF BATH, ENGLAND.

LIQUID-HYDROCARBON MOTOR.

SPECIFICATION forming part of Letters Patent No. 542,410, dated July 9, 1895.

Application filed May 19, 1893. Serial No. 474,827. (No model.) Patented in England December 6, 1890, No. 19,962.

To all whom it may concern:

Be it known that I, SAMUEL GRIFFIN, a subject of the Queen of Great Britain, residing at Kingston Iron Works, Bath, in the county of 5 Somerset, England, have invented certain new and useful Improvements in Liquid-Hydrocarbon Motors, (for which I have obtained Letters Patent in Great Britain, No. 19,962, dated December 6, 1890,) of which the following is a specification.

My present invention relates, first, to means for forming the combustible hydrocarbon spray used in the working of petroleum and other liquid-hydrocarbon motors, and in the 15 application of the same for forming the working or combustible charge in the motor-cylinder.

My invention also relates to an improved vaporizing-retort, means for heating the same, 20 and means for governing or controlling the speed of the engine.

In the accompanying drawings, Figures 1 and 2 show end and side elevations, respectively, of my improved petroleum or liquid-hydrocarbon motor. Fig. 3 shows a longitudinal section of the retort or heater with exhaust and charging passages attached. Fig. 4 shows plan of air-pump lever with mode of detachment for hand-operation. Fig. 5 shows a section 30 of the retort or heater on line 1 1, Fig. 3, together with the exhaust and inlet valves. Fig. 6 shows an enlarged view of governing mechanism, together with a portion of the retort or heater and spraying apparatus. Fig. 35 7 shows a plan of the exhaust and charging passages from the retort or heater into the motor-cylinder.

The cycle illustrated is that known as the "Beau de Rochas" or "double" cycle. Other 40 cycles, however, may be employed.

The same letters of reference indicate corresponding parts throughout.

a is the motor-cylinder; *b*, connecting-rod; *c*, crank; *d*, fly-wheel; *e*, petroleum-tank for 45 supply of ignition; *f*, pipe leading to ignition; *g*, air-pipe leading from air-reservoir (not shown) to ignition; *h*, retort or heater; *i*, air-supply to retort or heater; *j*, air-pump for supplying air to air-reservoir; *k*, air-pump 50 lever; *l*, eccentric-rod for actuating air-pump; *m*, lever for actuating air-pump by hand; *n*, removable pin for disengaging air-pump from

eccentric-rod; *o*, charging-valve; *o'*, governor-kicker for actuating charging-valve; *p*, exhaust-valve; *p'*, governor-kicker for actuating exhaust-valve; *q*, charging-valve lever; *r*, exhaust-valve lever pivoted at *r'*; *s*, casing containing exhaust and charging passages between retort or heater and motor-cylinder; *t*, ignition tube, case, or chimney; *u*, interior 60 of retort or heater for reception of spray to be vaporized; *v*, corrugated case, and *v'* case containing spraying apparatus; *w*, exhaust-space; *x*, air-space; *y*, exhaust-passage; *z*, charging-passage; *z'*, opening for passage or 65 outlet of flame when heating the retort or heater before starting the motor; *a'* *a'* *a'*, spraying apparatus; *b'*, air-pipe leading from spraying apparatus to air-valve; *c'*, petroleum or liquid-hydrocarbon supply-pipe connecting spraying apparatus with petroleum or liquid-hydrocarbon tank, (not shown;) *d'*, cam for actuating exhaust-valve; *e'*, governor-lever for actuating connecting-links; *e'*, connecting-link to governor; *e'*, governor; *f'*, 70 connecting-link from governor-lever to kicker; *g'* *g'*, levers for actuating air-valve *h'*; *i'*, connecting-link from governor-lever; *j'*, spiral spring; *j'*, lock-nuts; *k'*, port leading from charging and exhaust valves into motor-cylinder; *l'* *l'*, air-perforations; *m'* *m'*, male and female contact-pieces.

The operation is as follows: In preparing the motor for starting the pin *n* is unscrewed, disengaging the eccentric-rod *b*, thus allowing 85 the air-pump *j* to be actuated by hand by means of the movable handle *m*. A sufficient pressure of air being thus stored in the air-reservoir, (not shown,) the spraying apparatus *a'* *a'*, supplied with air and petroleum through 90 the pipes *b'* *c'*, respectively, is set in operation. The issuing spray being ignited in any convenient manner, the resultant flame passes through the interior of the retort or heater *u*, escaping by the passage *z* through the opening *z'* into the atmosphere. The corrugated casing *v* is by this means rapidly raised to a sufficiently high temperature to vaporize the hydrocarbon spray, which afterward passes through it. When the necessary temperature 95 has thus been attained the flame issuing from the spraying apparatus is extinguished and the opening *z'* is closed. The handle *m* is removed and the pump-lever *k* connected with

the eccentric-rod l , so that motion may be imparted to the pump by the action of the motor itself. The motor being now ready for starting, motion is given to the fly-wheel by any convenient means, hydrocarbon spray being at the same time allowed to escape from the spraying apparatus into the interior of the heater u , where, coming into contact with the hot walls of the corrugated casing v , it is at once vaporized, forming in combination with the atmospheric air contained therein a highly-explosive compound, which passes directly by the passage z past the charging-valve o into the motor-cylinder by the port k' , where it is compressed and fired, imparting motion to the piston and parts connected therewith and afterward exhausted in the usual manner. The exhaust-gases from the motor-cylinder pass through the port k' by the exhaust-valve p into the passage y , and thence through the space w of the heater h , escaping into the atmosphere by a passage at the end of the heater. (Not shown.) The hot exhaust-gases, in passing through the space w and enveloping the corrugated case v , will impart sufficient heat thereto to maintain the temperature necessary for vaporizing the combustible portions of the charge passing through it. The before-mentioned atmospheric air, which combines with the vaporized spray in the interior of the retort or heater u , forming the explosive or working charge, passes from the atmosphere through the supply-pipe i into the annular passage x , and thence through a number of small perforations $t' l'$ into the interior of the heater u , from whence it passes, mixed with the vaporised spray, into the motor-cylinder, as before described.

The atmospheric air in passing through the annular passage x will have its temperature sufficiently raised by the hot exhaust-gases in the space w to prevent any condensation of the before-mentioned spray or vapor with which it afterward mingles in the space w .

The igniting apparatus shown in Figs. 1 and 2 and illustrated by the parts lettered $e f g t$ is similar to the invention described in the specification of my British Letters Patent, No. 18,401 of 1890, and is not claimed herein. Any other form of igniting apparatus may be employed, and the igniting apparatus hereinafter described and claimed I have found especially suitable.

The apparatus for forming the hydrocarbon spray consists of an outer casing a' , which terminates in a fine nozzle and having a vertical jet or pipe a^2 , through which it is supplied with petroleum or liquid hydrocarbon from the enlarged end of the pipe c' . The central jet a^2 , which is adjustable longitudinally in the casing a' , is supplied with air under pressure from the before-mentioned air-reservoir, (not shown,) which passes into it through the air-valve h' and pipe b' . Its action is as follows: The pipe c' being supplied with liquid hydrocarbon from any convenient

source air under pressure is allowed to pass, as before described, through the central air-jet a^2 , forming, as it issues through the nozzle 70 of the casing a' , a partial vacuum in its interior. The liquid hydrocarbon contained in the pipe c' will consequently rise through the vertical jet or pipe a^2 , filling the interior of the casing a' , where, coming into contact with the air issuing from the central jet a^2 , it will be ejected as a fine spray through the nozzle which terminates the case a' . The amount and fineness of the spray are determined by the distance between the nozzle of the case a' 80 and the end of the central air-jet a^2 . The supply of spray is rendered intermittent or constant by the action of the air-valve h' , which opens or closes the air-supply in connection with and regulated by the governor, 85 as hereinafter explained.

The movement of the charging and exhaust valves, together with that of the air-valve, in connection with the spraying apparatus, is controlled by the action of the governor. 90

The exhaust-cam d' , which is attached to the "lay-shaft" of the engine, imparts motion to the lever r , which, through the medium of the kicker p' , lifts the exhaust-valve p at the proper time. This kicker, being hung on 95 a hinge at its upper end, is movable into and out of gear with the lever r by means of the connecting-link f' and lever e' ; which, by means of the link e^2 , receives its motion from the governor. The connecting-link f' passes 100 loosely through an eye in the end of the lever e' , being held in position by the nuts j' on one side and the spiral spring j' on the other. The lever g' , which is actuated by a cam (not shown) on the lay-shaft, imparts motion to 105 the air-valve h' by means of the swing-lever g' , this latter being also thrown into and out of gear with the air-valve by means of the connecting-link i' , which is also operated by the lever e' . 110

A raised projection on the circular part of the exhaust-cam d' (shown in position) serves to hold the lever r in gear with the exhaust-kicker p' (by means of the male and female contact-pieces $m' m^2$) without lifting it during a certain portion of its cycle, the spiral spring j' at the same time admitting of the movement of the lever e' without imparting motion to the connecting-link f' . 115

The mechanism for actuating the charging-valve o is, in all respects, similar to that just described for actuating the exhaust-valve, with the exception that the spiral spring j' may be dispensed with, the end of the connecting-link f' being jointed direct to the lever e' , the cam d' being also without any raised projection on its circular part for holding the lever q and kicker o' in gear. 120

The operation is as follows: Assuming the engine to be running at or below its normal speed the governors will be depressed, allowing both kickers $o' p'$ to be in gear with the levers q and r which actuate them. At the same time the lever g' will be in gear with

the air-valve h' , thus delivering the necessary spray for forming the combustible or working charge, as before described. The complete cycle of charging, compressing, igniting, and exhausting is thus continued until the velocity of the engine has increased sufficiently to cause the governor to lift, throwing the charging and exhaust-valve kickers o' and p' and swing-lever g^2 out of operation. Should the governor lift during that portion of the cycle between the ignition and exhaust of the working charge, the exhaust-valve kicker q' will be held in gear with the lever r by means of the raised projection on the circular part of the cam d' , as before described, until the exhaust-valve p is lifted and the spent gases discharged. During this period the movement of the lever e' will have put the spring j' into compression. Immediately, however, the exhaust-stroke is completed the kickers will be released by the action of the exhaust-cam d' , which allows the lever r to return to its normal position, the spring j' at the same instant drawing the kicker p' out of gear with the lever r . The charging, exhaust, and air-valves (being closed by springs of sufficient strength) will remain closed and inoperative on their respective seatings, thus preventing the formation of any further combustible or explosive compound in the interior of the retort or heater, and also preventing the entrance of any combustible or explosive compound or air into the motor-cylinder or the discharge of any gas therefrom. The engine will thus continue running by its own momentum until its speed is reduced, when the governors, again falling to their normal position, the cycle of operation before described will be recommenced.

40 I do not limit myself to the exact details herein described.

Having thus described my invention, what I claim as new, and desire to secure by Letters Patent of the United States, is—

45 1. In a liquid hydro-carbon motor, the combination of a retort or heater, means for heating the same internally preparatory to starting the motor and for producing a portion of the combustible or working charge, said means consisting of a spraying-apparatus arranged at one end of the retort or heater, and the motor connected with the retort or heater, substantially as set forth.

50 2. In a liquid hydro-carbon motor, the combination of a retort or heater, and means for heating the same internally preparatory to starting the motor and for producing a portion of the combustible or working charge, said means consisting of a spraying-apparatus arranged at one end of the retort or heater, and an opening at the other end of the same communicating directly with the atmosphere, and provided with a suitable removable closure, substantially as set forth.

55 3. In a liquid hydro-carbon motor, the combination of a retort or heater, provided with an inner central case and with a jacket com-

pletely encircling the same and forming an annulus adapted for the exhaust gases to pass through, means for heating the interior of the central case preparatory to starting the motor and for producing a portion of the combustible or working charge, such means consisting of a spraying-apparatus arranged at one end of the retort or heater and adapted to eject a fine spray of intimately mixed air and liquid hydro-carbon into the central case of said retort, and the motor connected with said retort, substantially as set forth.

4. In a liquid hydro-carbon motor, the combination of a retort or heater, provided with an inner central case and with a jacket surrounding the same and forming an annulus adapted for the passage of exhaust gases, an additional outer jacket or cover around the aforesaid jacket and forming a third separate chamber or space for the passage of the air used in forming the working charge, said third or outer chamber having communication at one end with one end of the chamber in the central case, a spraying-apparatus arranged at said end and adapted to eject a fine spray of intimately mixed air and liquid hydro-carbon into the central case of the retort, and the motor connected with the retort, substantially as set forth.

5. In a liquid hydro-carbon motor, the combination of a retort or heater having an interior central case provided with longitudinal corrugations, a jacket encircling the case and forming an annulus or space for the passage of the exhaust gases, means for heating the retort, and the motor connected with the retort, substantially as set forth.

6. In a liquid hydro-carbon motor, the combination of a retort or heater having an inner central case provided with longitudinal corrugations, a jacket surrounding the case and forming a space for the passage of the exhaust gases, an additional jacket or outer cover for said jacket forming a space or annulus for the passage of air used in forming the working charge, said outer space or annulus communicating with one end of the chamber of the inner case, a spraying-apparatus arranged at said end and adapted to eject a fine spray of mixed air and liquid hydro-carbon into the inner case of said retort, and the motor connected with the retort, substantially as set forth.

7. In a liquid hydro-carbon motor, the combination of a retort or heater, said retort or heater being composed of an inner central case, a jacket surrounding said case and forming a space for the passage of exhaust gases and an additional jacket outside of the aforesaid jacket forming a space or annulus adapted for the passage of air used in forming the working charge, said outer space having communication with one end of the chamber of the central case, a spraying-apparatus located at said end and adapted to eject a fine spray of intimately mixed air and liquid hydro-car-

- bon into the interior of said inner case, the motor, and a casing containing exhaust and charging passages, said casing being arranged between the retort or heater and the motor, the exhaust passage having communication with the space between the first-named jacket and the inner case and said charging passage communicating with the chamber of said case, substantially as set forth.
10. 8. In a liquid hydro-carbon motor, the combination of a retort or heater, a motor connected by means of charging and exhaust passages with the retort or heater, charging and exhaust-valves arranged in said respective passages, a governor, and mechanism connected with the governor and said valves, whereby by the action of the governor the valves are rendered inoperative and remain closed when the normal velocity of the engine is exceeded, substantially as set forth.
15. 9. In a liquid hydro-carbon motor, the combination of a retort or heater, a motor connected by means of charging and exhaust-
- passages with said retort or heater, charging and exhaust valves arranged in the passages, 25 the governor, and mechanism arranged between the governor and said valves whereby by the action of the governor the valves are rendered inoperative and remain closed while the normal velocity is exceeded, said mechanism comprising cams arranged on the lay-shaft of the engine, fulcrumed levers adapted to be actuated from one end by means of said cams, contact-pieces arranged respectively at the other ends of said levers and on said 30 valves, a bell-crank or governor lever connected with the governor, and a connecting-rod or link between the contact-pieces of the exhaust valve and the said bell-crank lever, the latter being loosely connected with said 35 link, substantially as set forth.

SAMUEL GRIFFIN.
